UNITED STATES PATENT OFFICE.

HUTCHINSON L. BEVIER, OF DULUTH, MINNESOTA; THE FIRST NATIONAL BANK OF DULUTH EXECUTOR OF HUTCHINSON L. BEVIER, DECEASED.

HEATER.

Application filed January 7, 1926. Serial No. 79,876.

My invention relates to heaters and has for its object the provision of an improved stove with a relatively large radiation surface so formed as to direct a large proportion 5 of the radiated heat horizontally. It has for a further object the provision of a stove containing an improved heat resisting horizontally serrated core whereby the hot products of combustion are guided into contact with correspondingly serrated radiator side walls. It consists also in providing a stove in which the major part of the side walls above the fuel chamber may be opened 10 outwardly to give full access to their inner faces and to the outer face of said core for 15 the purpose of cleaning or repairing the same. With these and other objects in view, it consists of the structures, combinations, and arrangements of parts hereinafter described and claimed.

In the drawings, Fig. 1, is a central vertical section through a stove embodying my said invention. Fig. 2, is a top plan view of the same. Fig. 3, is a top plan view of the 25 same showing the side walls in open position, and Fig. 4, is a front elevation of said invention.

In the drawings, 1 is a base containing an ash chamber 1^a, and a fuel chamber 1^b, 30 which ash chamber is adapted to be closed by a clean-out door 2 and by any suitable draft-control device, as the door 3. A fueling door 4 is provided for said fuel chamber in which door is preferably positioned a 35 ventilator as 5. Said base also contains a grate of any suitable structure, as 6. Extending above said base are serrated or corrugated side walls, the lower end 7 of which is preferably stationary and formed or erected 40 upon said base, and the upper or major portions of which, as 7^a and 7^b are adapted to open outwardly and are preferably pivoted upon a post 8. Said side walls are so corrugated, serrated or indented as to present 45 the appearance of a series of superposed funnel-shaped sections wherein the upper face of each section is horizontal and the sides of each section incline downward and inwardly at approximately forty-five degrees. Said portions 7^a and 7^b are divided 50 from each other adjacent to said post and at the opposite side of the stove from said post, and at their opposing edges are provided with overlapping lips or flanges as 7^c, 7^d.

Supported in any suitable manner within

the chamber formed by said side walls, is a heat resisting core of any suitable structure or material, as a metal shell 9, filled with asbestos 10, the sides of which are corrugated to correspond with and extend parallel to 60 the corrugations in the inclosing side walls 7, 7^a and 7^b from which the side walls of said core are spaced a short distance so as to form a thin annular flue 11 between said core and said inclosing walls, whereby the hot products of combustion are guided into direct contact with said inclosing walls, and especially with the horizontal faces thereof. In Fig. 1, of the drawing the space between the core and the inclosing walls 7^a and 7^b is 65 broadened in order to more clearly show the several parts. Said core may be supported in any suitable manner, as by lugs or pins 12 extending from said base or from the stationary portion of said side walls.

Supported in any suitable manner above said core, as by posts 13, mounted on said core is a stationary chimney pipe connection 14 preferably provided with a flange 14^a corresponding in diameter to the opening at 80 the upper ends of said side walls. Thus when the side walls are opened as shown in Fig. 3, the chimney connection will be supported by said core. Said flange and side walls are provided with lips, as 14^b and 7^e, 85 respectively, adapted to overlap in operative position.

When said side walls are closed, they may be held together by any suitable means, as by hooks 15 mounted upon one of the sides 90 and adapted to engage lugs 16 upon the other of the sides.

If desired, polished reflector plates 17 may be secured in any suitable manner to any or all of the outer inclined faces of said 95 sides to more effectively reflect the heat radiated from the horizontal faces of said sides and direct it horizontally. But if desired said polished reflectors may be omitted.

I am aware that stoves or heaters with 100 corrugated sides are old in the art, but I am not aware of any in which the corrugations or indentations present horizontal surfaces opposed by surfaces directed at an angle of substantially forty-five degrees whereby 105 heat from said horizontal surfaces is reflected and directed by the inclined surfaces in a horizontal direction. Nor am I aware of prior stoves with corrugated sides in 110 which alternate faces of the indents are

horizontal and in which a correspondingly indented or corrugated core is adapted to guide the hot products of combustion into direct contact with the interior sides of the horizontal faces of said side walls.

What I claim is:

In a heater, the combination of a base containing a fuel chamber; a core extending above said fuel chamber; means for supporting said core; side walls comprising a stationary portion extending up from said base and movable portions extending up from said stationary portions; a post adapted to pivotally support said movable portions; a chimney pipe extending above said core and provided with a horizontal flange; means for supporting said pipe; said mov-

able portions having lips formed upon their opposing edges adapted to overlap each other when said movable portions are in 20 closed or operative position, the upper ends of said movable portions of said side walls having lips formed thereon adapted to overlap a lip formed upon said flange; the lower ends of said movable portions having lips 25 formed thereon adapted to overlap a lip formed upon the upper edge of said stationary part of said side walls; and means for securing said side walls in closed or operative position.

In testimony whereof, I hereunto affix my signature.

HUTCHINSON L. BEVIER.
